UNITED STATES PATENT OFFICE.

GEORGE H. PERKINS, OF WINTHROP, MASSACHUSETTS, ASSIGNOR TO JOSEPH W. WOODS & SONS COMPANY, OF BOSTON, MASSACHUSETTS, A CORPORATION OF MASSACHUSETTS.

DESIGN FOR A WOVEN FABRIC OR SIMILAR ARTICLE.

47,671.

Specification for Design.

Patented Aug. 3, 1915.

Application filed May 24, 1915. Serial No. 30,233. Term of patent 7 years.

To all whom it may concern:

Be it known that I, GEORGE H. PERKINS, a citizen of the United States, residing at Winthrop, in the county of Suffolk and State of Massachusetts, have invented a new, original, and ornamental Design for Woven Fabric or Similar Article, of which the following is a specification, reference being had to the accompanying drawing, forming part hereof.

The figure is a plan view of a portion of a woven fabric illustrating my new design.

I claim:

The ornamental design for woven fabric or similar article, as shown.

GEORGE H. PERKINS.

Witnesses:

WM. NEWELL,
STEPHEN A. SMITH.
